United States Patent Office

Des. 179,368
Patented Dec. 11, 1956

179,368

PLATE OR SIMILAR ARTICLE

A. Baker Barnhart, New York, N. Y., assignor to The Rosenthal-Block China Corporation, New York, N. Y.

Application May 21, 1956, Serial No. 41,549

Term of patent 14 years

(Cl. D44—15)

The figure is a plan view of a plate or similar article of conventional configuration, showing my new design.

I claim:

The ornamental design for a plate or similar article, as shown and described.
